UNITED STATES PATENT OFFICE

ERNEST T. BECK, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A TABLE FORK OR SIMILAR ARTICLE

Application filed April 15, 1930. Serial No. 35,258. Term of patent 14 years.

To all whom it may concern:

Be it known that I, ERNEST T. BECK, a citizen of the United States, residing at Meriden, county of New Haven and State of Connecticut, have invented a new, original, and ornamental Design for a Table Fork or Similar Article, of which the following is a specification, reference being had to the accompanying drawings, forming a part thereof.

Fig. 1 is a front elevation of a table fork showing my new design; and

Fig. 2 is a side view of the same.

The dominant feature of the design is a table fork having substantially the configuration shown, and wherein the tines are approximately one-fifth of the total length of the fork.

I claim:

The ornamental design for a table fork or similar article, as shown, and described.

ERNEST T. BECK.
